MECHANICAL PRESSURE OPERATED
ACTUATING DEVICE

Ralph W. Peters, Hollywood, Calif.

Application September 6, 1950, Serial No. 183,450

1 Claim. (Cl. 74—469)

1

This invention relates to a mechanical pressure operated actuating device, and, more particularly, to such a device adapted to energize or actuate associated mechanism in either of two directions in accordance with the direction of the application of mechanical pressure thereto.

An important object of this invention is the provision of a device for actuating a lever or the like, whereby to operate mechanism, such, for example, as the opening and closing mechanism for mechanically operated garage doors which will actuate such mechanism upon application of pressure thereto, the direction of actuation being governed by the direction of application of pressure.

An additional object of the invention is the provision of a device of this nature characterized by a plurality of hingedly connected movable plates so arranged as to apply pressure selectively in either of two directions to an operating rod, whereby to actuate mechanism associated therewith.

A further object of the invention is the provision of a device of this character having means whereby the operating rod or lever is automatically returned to central or neutral position upon release of pressure thereon.

Still another object of the invention is the provision of such a device which will be sturdy and durable in construction, reliable and efficient in operation, and relatively simple and inexpensive to manufacture, assemble, and install.

Other objects reside in the combinations of elements, arrangements of parts, and features of construction, all as will be more fully pointed out hereinafter and disclosed in the accompanying drawing wherein there is shown a preferred embodiment of this inventive concept.

In the drawings:

Figure 1 is a top plan view of one form of device embodying the instant invention shown in installed position.

Figure 2 is a sectional view taken substantially along the line 2—2 of Figure 19 viewed in the direction indicated by the arrows.

Figure 3 is a top plan view of the device, the top plates thereof being removed.

Figure 4 is a sectional view taken substantially along the line 4—4 of Figure 1 as viewed in the direction indicated by the arrows, and

Figure 5 is a fragmentary side elevational view showing a constructional detail.

Similar reference characters refer to similar parts throughout the several views of the drawings.

2

Referring now to the drawings in detail, there is generally indicated at 10 a rectangular frame comprised of side angle iron members 11 and similar end members 12, the frame being adapted to be inset in a recess 13 in a concrete drive 14 or the like. Extending transversely between the side members 11 at opposite ends adjacent end members 12 are two horizontally positioned rods 15, and extremities 16 of which project outwardly beyond side members 11 to form pivots which extend into slots 17 formed in depending flanges 18 at the extremities of relatively flat end plates 19. End plates 19 are disposed in opposite relation, and are provided at the extremities thereof 10 opposite flanges 18, with staggered portions 20 reverted to form loops, and coacting with oppositely staggered portions 21 of a central plate 22, the portions 21 also being reverted to provide in combination with the reverted portions 20 aligned bores for the reception of hinge pins 23, the entire assembly forming three hingedly connected sections pivotally connected at its opposite ends to the frame 10. Extending transversely across the center of frame 10 and journaled in side members 11 is an operating rod or lever 25 provided at its mid point with oppositely extending lugs 26 each provided with an eye adapted for the reception of one end of a coiled spring member 27, the opposite end of each member 27 being anchored in an eye bolt 28 engaged in a suitable threaded aperture in a transverse bar 29, and secured therein as by a wing nut 30. The arrangement is such that upon rotation of the rod 25, in a manner to be more fully pointed out hereinafter, the springs 27 will serve to bias, through lugs 26, the rod 25 back to central or neutral position.

Fixedly secured to rod 25 on opposite sides of lug 26 are a pair of levers 35 each of which is provided at its upper extremity with a transversely extending pin or axle 36 upon which is mounted a roller 37, the rollers being normally in engagement with the under surface of plate 22 at substantially its mid point.

As best shown in Figure 3 each of side members 11 is provided with a pair of stub axles or pins 40 projecting inwardly therefrom which carry rollers 41, adapted to be engaged by plates 19 when the latter are in one position of adjustment, as will be more fully pointed out herein-after.

One extremity of rod 25 may extend outwardly beyond frame 10, and have secured thereto a lever 42, or any other suitable member which it is desired to move in either of two directions for

the purpose of actuating any desired mechanism. From the foregoing, the operation of the device should now be readily understandable. When pressure is applied to one of plates 19, from either direction, as, for example, from the direction indicated by the arrow in Figure 2, the plate is depressed to flat position as shown by dotted lines until it rests on the rollers 41. This depression will simultaneously cause, through the hinged connection formed by pin 23, an inclination of the plate 22 to the position shown, or downwardly inclined in the direction of the application of pressure. As the wheel of the vehicle advances onto plate 22, the latter will obviously be depressed, and the pressure exerted thereon will cause the rollers 37 to move away from the direction of the application of pressure, rotating rod 25 and, hence, actuating its associated mechanism. As the vehicle wheel leaves plate 22 the second plate 19 will be similarly depressed releasing the pressure on levers 35, and permitting the springs 27 to act to return levers 35 to upright position and rod 25 to central or neutral position.

Obviously upon the application of pressure from an opposite direction the reverse action will be effected, and the rod 25 rotated in an opposite direction, again away from the direction of the application of force.

From the foregoing it will now be seen that there is herein provided an improved mechanical pressure operated actuating device which accomplishes all the objects of this invention, and others, including many advantages of great practical utility and commercial importance.

As many embodiments may be made of this inventive concept, and as many modifications may be made of the embodiment herein shown and described, it is to be understood that all matter herein is to be interpreted merely as illustrative and not in a limiting sense.

I claim:

In a device of the character described a frame, an operating rod extending transversely across said frame, levers extending from said rod, springs means associated with said rod manually biasing said levers to upright position, additional transverse rods extending across the ends of said frame and outwardly thereof, each of said plates having slotted side flanges, the ends of said additional transverse rods engaging in the slots of said flanges to pivotally secure said end plates at one end to said frame, and a center plate pivotally secured between said end plates whereby pressure on one of said end plates biases said levers in one direction and tilts said center plate, and subsequent pressure on said center plate moves said levers in a direction opposite to the direction of application of pressure to rotate said rod in said direction.
